COMBINED BIRD SEED HOPPER AND DISPENSER

George Siggins, East Orange, N. J.

Application April 5, 1954, Serial No. 29,873

Term of patent 14 years

(Cl. D31—2)

FIG. 1

FIG. 2

FIG. 3

FIG. 4

Figure 1 is a perspective view of a combined bird seed hopper and dispenser showing my new design;

Figure 2 is a front elevational view of the combined bird seed hopper and dispenser shown in Figure 1;

Figure 3 is a side elevational view thereof; and

Figure 4 is a vertical longitudinal sectional view thereof taken approximately on the plane of the line 4—4 of Figure 2.

I claim:

The ornamental design for a combined bird seed hopper and dispenser, as shown.
